[57] CLAIM

The ornamental design for a microphone stand, substantially as shown.

DESCRIPTION

FIG. 1 is a perspective view showing my new design for a microphone stand;

FIG. 2 is a rear elevational view thereof;

FIG. 3 is a side-elevational view thereof;

FIG. 4 is a front elevational view thereof;

FIG. 5 is a top plan view thereof;

FIG. 6 is a bottom view thereof; and

FIG. 7 is a transverse cross-sectional view of the base thereof, with microphone support broken away.
